UNITED STATES PATENT OFFICE.

THEODORE TAYLOR, OF LA GRANDE, OREGON.

CUTTER-BAR FOR REAPING AND MOWING MACHINES.

SPECIFICATION forming part of Letters Patent No. 259,602, dated June 13, 1882.

Application filed January 10, 1882. (No model.)

To all whom it may concern:

Be it known that I, THEODORE TAYLOR, of La Grande, in the county of Union and State of Oregon, have invented certain new and useful Improvements in Cutter-Bars for Reaping and Mowing Machines, of which the following is a full, clear, and exact description.

The object of my invention is to provide for convenient attachment and removal of the knives of cutter-bars; to which end the invention consists in a cutter-bar provided with studs for engaging the knives and a clamping-piece for securing them, as hereinafter described and claimed.

Reference is to be had to the accompanying drawings, forming a part of this specification, in which similar letters of reference indicate corresponding parts in all the figures.

Figure 1 is a front elevation of a cutter-bar embodying my invention. Fig. 2 is a sectional plan view of the same. Fig. 3 is a plan view in section on line $\alpha\alpha$ of Fig. 1, and with the clamps opened; and Fig. 4 is a cross-section on line $\alpha\alpha$ of Fig. 3.

A is the cutter-bar, consisting of bottom plate, a , back plate, b , and cap-plate c , which may be of a single piece or two or more pieces secured together. On the bottom plate, a , are studs d , which extend above the plate a distance equal to the thickness of the knives or sections e . The studs may be round, square, oblong, or other shape best suited for their purpose, and they may be riveted to the plate or screwed therein, so as to allow removal by a wrench.

The knives or sections e are formed with holes or recesses to fit the studs, so that when the knives are placed on the bottom plate they are engaged by the studs and thus kept in place.

To clamp the knives and prevent them from rising off the studs, the clamping-pieces f are provided, such pieces being strips of a size to fill the space between the upper side of the knives and under side of the cap-plate c . In Figs. 1, 2, and 3 there are two pieces f shown,

45 attached at one end by a hinge-pin, g , so that

they can be turned in and out of place. One piece f laps on the other at the end when closed, and a bolt, h , passing through the cutter-bar and outer clamp, retains both in place; or a screw may be used for the same purpose. 50

To allow removal of the knives, the bolt or screw h will first be taken out and the clamps f then swung out.

A hole, i , is provided in back plate, b , for insertion of a suitable tool to push out the 55 clamps.

The advantages of this cutter are briefly as follows: The cutters, or any number of them, can be readily removed, as is often desirable. The cutters can be more rapidly and perfectly 60 ground when removed from the bar. There are no screws liable to become loose by the vibration. Only one bolt has to be loosened in removing the cutters.

I am aware that it is not new to provide the 65 bottom plate of a cutter-bar with studs, which enter perforations in the knives, and to detachably secure the top plate of the cutter over the knives by screws or bolts, and therefore do not claim such; but

70 What I do claim, and desire to secure by Letters Patent, is—

1. The combination, with a cutter-bar provided with studs on its bottom plate, and knives having recessed edges, of hinged clamping-pieces adapted to be secured in the space between knives and cap-plate, substantially as herein shown, and described, and for the purpose set forth. 75

2. The combination, with the cutter-bar A, 80 having studs d on its bottom plate, a , and the knives e , having recessed edges, of the clamps f , hinged to the ends of the said cutter-bar, and having overlapping ends, and the fastening-bolt h , substantially as and for the purpose set forth. 85

THEODORE TAYLOR.
